CLAIM

The ornamental design for an electrical female terminal, as shown and described.

DESCRIPTION

FIG. 1 is a top and front perspective view of an electrical female terminal according to the claimed design;

FIG. 2 is a top and back perspective view of the electrical female terminal according to the claimed design;

FIG. 3 is a left side elevational view of the electrical female terminal according to the claimed design;

FIG. 4 is a right side elevational view of the electrical female terminal according to the claimed design;

FIG. 5 is a top elevational view of the electrical female terminal according to the claimed design;

FIG. 6 is a bottom elevational view of the electrical female terminal according to the claimed design;

FIG. 7 is a front elevational view of the electrical female terminal according to the claimed design; and,

FIG. 8 is a back elevational view of the electrical female terminal according to the claimed design.

The broken lines are included for the purpose of illustrating environmental structures and form no part of the claimed design.

1 Claim, 4 Drawing Sheets
